UNITED STATES PATENT OFFICE

170,522

COMBINED CLEANING TISSUE AND LAMP HOUSING

Harold D. Brown, Gridley, Kans.

Application May 25, 1953, Serial No. 25,185

Term of patent 14 years

(Cl. D4—3)

To all whom it may concern:

Be it known that I, Harold D. Brown, a citizen of the United States, residing at Gridley, State of Kansas, have invented a new, original, and ornamental Design for a Combined Cleaning Tissue and Lamp Housing, of which the following is a specification, reference being had to the accompanying drawing, forming a part hereof.

Fig. 1 is a $\frac{3}{4}$ bottom perspective view of a combined cleaning tissue and lamp housing embodying my new design;

Fig. 2 is a front view of the housing;

Fig. 3 is a rear view of the housing;

Fig. 4 is a top plan view of the housing; and

Fig. 5 is a vertical sectional view taken along the line 5—5 of Fig. 2.

I claim:

The ornamental design for a combined cleaning tissue and lamp housing, as shown.

HAROLD D. BROWN.
